UNITED STATES PATENT OFFICE.

JAMES THOMAS, OF NEWARK, NEW JERSEY.

COMPOUND TOOL FOR PAINTERS' USE.

SPECIFICATION forming part of Letters Patent No. 259,245, dated June 6, 1882.

Application filed August 24, 1881. (No model.)

To all whom it may concern:

Be it known that I, JAMES THOMAS, a resident of Newark, in the county of Essex and State of New Jersey, have invented certain new and useful Improvements in a Compound Tool for Painters' Use; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

The object of this invention is to provide a convenient and reliable support for a paint-pail, capable of being adjusted on the side of a building or of being suspended upon the rung of a ladder upon which a painter may be standing while at work.

When painting the side of a building by the means heretofore employed in such cases, a painter standing and working upon a ladder placed against the side of a building has been compelled sometimes to hang his paint-pail

two or three rungs below his feet, out of convenient reach, especially when the ladder was placed in close proximity to the building, or when the painter was standing upon the top rung of said ladder. By my improved device he is enabled to secure his paint-pail upon the side of the house at any appropriate or convenient part thereon, obviating the necessity of climbing up and down said ladder to take a fresh dip of paint, as when said pail hangs from the ordinary S-shaped hook upon the rung of said ladder beneath his feet, all of which will be well understood. Thus by means of my device labor and consequent expense are saved and great inconvenience avoided.

The invention consists in the arrangement and combination of parts substantially as set forth, shown, and finally definitely embodied in the claims.

Referring to the accompanying drawings, in which similar letters of reference indicate like parts in each of the figures, Figure 1 is a view of my device when placed on the side of a building, and Fig. 2 a view of the same when suspended on the rung of a ladder.

In carrying out my invention I form a body

or handle, C, having a shape substantially as shown, upon one end of which is secured a screw, m, pivoted at v, and adapted to be opened and closed after the manner of a clasp-knife. Upon the same pivot may also be secured a 55 knife-blade, n, also arranged to clasp in the usual manner.

Upon the under edge of the handle C, at a point, e, approximately the middle of the same, is pivoted a hook, r, adapted, when opened, to engage with the rung w of the ladder A, as shown in Fig. 2, and when closed to clasp the rounded extremity of the handle and be carried in the pocket. Said hook has also a roughened or toothed portion, r', adapted to engage 65 with the clapboards or side of the building B, as will be hereinafter explained.

The circular extremity of the body C forms a box, into which is secured and arranged a self-winding tape-measure, q. The upper edge 70 of the rounded extremity of the body or handle is recessed in such a manner as that a hook, o, is formed, of sufficient size to receive and hold the bail e.

The operation of the device thus described is 75 as follows: When I wish to secure the pail to the rung w of the ladder A the hook r is placed thereon, and the handle C depends, as shown in Fig. 2, the hook o facing upward. The bail e is then hung upon the said hook o, the knife-blade n so extending over the bail e as to prevent the same from being disengaged, as will be understood upon reference to the same figure.

In adjusting my improved support upon the 85 side of a building I unclasp or open the screw m and secure the same in the boards B, the toothed hook rr' being brought to bear against the boards B, thus forming a brace, when the pail may be hung upon the support, which will, 90 by its weight, have a tendency to drive the teeth r' more firmly into the building B, and so brace and support the device, as will appear upon reference to Fig. 1.

The knife-blade, in addition to the function 95 already cited, will be useful in its usual capacity. The tape-measure, also, will be useful for its usual measuring purposes. The device, as a whole, forms a compound tool for painters' use, embodying and combining a paint-pail 100

support adapted to furnish means whereby a paint-pail may be supported upon the clap-boards of a house, a folding S-shaped or pot hook adapted to connect the pail to the rung 5 of a ladder, a knife-blade, and tape-measure.

The compound tool thus formed will be of great convenience to the painter, for, in addition to the advantages already detailed, he will have an article of constant usefulness, not only 10 when in the act of painting, but when estimating the cost of work and in making preparation for work, all as will be understood and appreciated.

Having thus described my invention, what I 15 claim, and wish to secure by Letters Patent, is—

1. An adjustable support for paint-pails, comprising a body or handle, C, having a hook or recess, o, therein, a toothed hook, r r', and 20 a screw, m, arranged and operating substantially as and for the purposes set forth and shown.

2. The combined paint-pail support, pot-hook, and knife-blade as an article of manufacture, arranged and operating substantially 25 as and for the purposes herein set forth and shown.

3. The combined paint-pail support, pot-hook, knife-blade, and tape-measure as a compound tool, substantially as and for the purposes herein set forth and shown.

4. The combined paint-pail support, pot-hook, and tape-measure, arranged and operating 30 in a compound tool, substantially as and for the purposes set forth and shown.

5. The combination, in an adjustable support for paint-pails, of the handle C, having a hook or recess, o, therein, a toothed hook, r r', pivoted upon the body at e, a screw, m, and knife-blade n, all arranged and operating substantially as and for the purposes set forth and shown.

6. A paint-pail hook having a handle with a recess therein, adapted to receive the pail-bail, and a hook secured in said handle, adapted 45 to engage with the rung of a ladder, substantially as and for the purposes set forth and shown.

7. A paint-pail support and pot-hook, combined and adapted to operate substantially as and for the purposes set forth and shown.

8. A paint-pail support having means thereon adapted to be secured to the vertical wood-work of a house, and an S-shaped hook, combined substantially as and for the purposes set 55 forth and shown.

9. The combination, with the notched handle adapted to receive the pail-bail, and having means thereon adapted to be secured to the vertical wood-work of a house, of a hook 60 having means thereon enabling said hook to brace said handle, all substantially as and for the purposes set forth.

In testimony that I claim the foregoing I have hereunto set my hand this 16th day of 65 August, 1881.

JAMES THOMAS.
